FOLD-MAKING MACHINE

Leonard Hopkins, Holyoke, Mass.

Application January 8, 1936, Serial No. 58,081

5 Claims. (Cl. 242—56)

This invention relates to improvements in machines for packaging material and is directed more particularly to improvements in machines for rolling up lengths of material such as paper or the like.

5 The principal objects of the invention are directed to the provision of a machine for winding or rolling up lengths of material such as paper or the like into a fold or bolt.

10 According to special features of the invention the material is cut from a roll into lengths, then wound into a fold.

15 The machine is particularly adapted for paper such as crepe paper which is sold in what are called folds. A fold is a length of paper rolled up in the form of a relatively flat package or bolt which is inserted in a flat tube-like binder.

20 Paper such as referred to is sold at relatively low cost so that it is necessary in order to meet the requirements of low cost to package the paper at low cost. The machine of the invention embodies novel features of construction and arrangement to enable high speed operation and thereby facilitate the desired low cost production.

25 It is characterized by many novel features of construction to facilitate efficiency in operation and has been found to be capable of mechanically performing the many operations heretofore performed by hand.

30 In the drawings,

Fig. 1 is a side elevational view of the machine of the invention;

Fig. 2 is a transverse sectional view through the cutter mechanism of the machine shown in

35 Fig. 1;

Fig. 3 is a side elevational view of the cutting end of the machine taken at the side opposite that shown in Fig. 1;

Fig. 3a is a detail side elevational view of the 40 cutting mechanism of the machine shown in

Fig. 1;

Fig. 4 is a sectional elevational view on the line 4—4 of Fig. 1;

Fig. 5 is a detail sectional view showing the 45 inner ends of the co-operating web winding elements of the winding mechanism of the machine;

Fig. 6 is a sectional plan view of the machine taken on the line 6—6 of Fig. 4;

Fig. 7 is a sectional elevational view on the 50 line 7—7 of Fig. 4;

Fig. 8 is a sectional elevational view on the line 8—8 of Fig. 6;

Fig. 9 is a sectional elevational view on the 55 line 9—9 of Fig. 6;

Fig. 10 is an elevational view of the package stacking mechanism;

Fig. 11 is an enlarged sectional view through one of the winding heads of the machine;

Fig. 12 is a sectional view on the line 12—12 of 5 Fig. 11;

Fig. 13 is a similar view on the line 13—13 of Fig. 11;

Fig. 14 is an elevational view of the co-operating 10 discs of the winding mechanism;

Fig. 15 is a diagrammatic sectional view to explain certain features of the winding mechanism; and

Fig. 16 is a diagrammatic elevational view to 15 explain the operation of the machine.

Referring now to the drawings in detail the invention will be fully described and to facilitate a clear understanding of the novel features of the machine and its operation reference will first be 20 made to Fig. 16.

A length of material such as paper is represented by L. This has been severed from a web in the form of a roll. The length is wound or rolled into what for convenience may be called a fold F which is relatively flat as shown and resembles a bolt of cloth. As will be explained, there are two winding mechanisms so that successive lengths are alternately fed to and wound up by the said mechanisms. This facilitates 25 speed in production.

It will be understood that the machine is adapted for operation on various materials wherefore the mention of paper is not to limit the scope of the invention to paper alone.

After the folds F are formed they are fed forwardly in the machine in the direction of the arrow a to a position indicated by A. Then the folds F are fed transversely in direction of arrow b to the position B wherein they are buckled, bent longitudinally or contracted for inserting into a 30 band or tube T.

The tubes T are in a flat condition in a stack and are fed forwardly from the stack in direction of arrow x to a receiving position C where they are opened up to receive the folds F. Successive buckled folds F are fed transversely in the direction of arrow c into successive opened up tubes T. Mechanism to be described opens the tubes and when the folds are inserted therein the opening up mechanism releases them and then the folds in the tubes comprise packages P which are fed downwardly in direction of arrow y to a stack from which the operator removes them.

50 A more detailed description of the machine will now follow.

Looking at the front side of the machine in Fig. 1 there is a rear end frame such as 2, a forward end frame 4, and other frames 2' and 4' at the rear side of the machine spaced from and secured to the said frames 2 and 4. These frames include upper and lower parts as shown. The frames 4 and 4' are secured to a transversely and longitudinally extending base such as 6 which is secured to frames 2 and 2'. Other spaced frame parts 3 and 3' are located at the front end of the machine forwardly of parts 4 and 4' and beyond them as shown in Figs. 6 to 9 inclusive. It will be understood that the frame parts may take any form desired.

15 The paper or other material is cut into lengths at the rear end of the machine and is led to the forward end where it is rolled into folds. The folds are then fed transversely during which movement they are buckled and inserted in the tubes.

20 Roll supports 10 extend rearwardly from the frames 2 and 2' and are notched, as shown, to receive an arbor such as 12 of a roll of paper such as R. Upper bars 14 carry a rod 16 to which is attached a flexible strap 18 that bears on the roll R. A weight 20 on strap 18 tensions it so that it serves as a brake to prevent over-travel of the roll R. The web W of paper from the roll R passes over a lower roll 22 having a shaft 24 journaled in the frames 2 and 2'. Another roll 23 above roll 22 co-operates therewith to feed the web W into the machine as will later appear.

25 The machine may be driven in any desired manner but for purposes of description a motor 26 for that purpose is shown on member 6, see Figs. 2 and 3.

30 A shaft 28 is journaled in brackets 29' fixed to frames 4 and 4' and carries a pulley 30 operably connected by a belt 32 to a pulley 34 of the motor 26. An upper shaft 36 journaled in frames 4 and 4' carries a pulley 38 which is connected by a belt 40 to a pulley of a shaft 42 journaled in frames 2 and 2'. A pulley 29 on shaft 28 has a belt 31 thereon which engages pulley 38. A pulley 44 on shaft 42 carries a belt 46 which passes over a pulley 48 on shaft of roll 22. By means of the connections described lower feed roll 22 is rotated.

35 A rotatable knife carrier 50 (see Fig. 2) has a shaft 52 journaled in frames 2 and 2' and carries a knife 54 co-operating with a stationary knife 56 for severing the web W into lengths. The knife bar is rotated (see Fig. 3) from shaft 42 by means of a gear 60 on its shaft which intermeshes with a gear 62 on shaft 64 which in turn is operatively connected by gears 66 and 68 to shaft 42. The knife mechanism operates in the well-known manner to cut or sever the web into successive lengths.

40 The upper roll 23 is mounted for movement relative to lower roll 22 by being journaled in levers 70 which are pivoted to frames 2 and 2' (see Figs. 1 to 3a). A latch 72 pivoted at 74 to a swinging lever 71 on the forward side of the machine has its lower end arranged to rest on a stop 76 as shown in Fig. 3a, whereby the roll 23 is held out of contact with the lower roll 22. By pressing outer end 73 of latch 72 the lower end of latch 72 is moved from off stop 76 so that the levers carrying the upper roll swing and allow the upper roll 23 to come to rest on lower roll 22 whereby they co-operate for feeding the paper. The roll 23 is automatically lowered by means of an arm 78 rigidly associated with arm 80 swingable on a pivot 82. A cam 84 having a nose 86 on shaft 64 is arranged by rotation of shaft 64 to

swing arms 88 and 78 so that arm 78 strikes a pin 88 on part 72 to swing it from off port 76.

5 The length of paper L is fed forwardly by means of a belt conveyor mechanism now to be described.

Shafts 90, 92 and 94 are rotatable in frames 2 and 2' and carry rolls 90', 92' and 94'. Levers 96 on shaft 90 have rolls 96' in their outer ends. Rolls 100, 102, 104 and 106 are journaled in the frames 4 and 4' as is a roll 108. Levers such as 110 adjacent each frame 4 and 4' are oscillatable on shaft 112 and carry rolls 114 and 116 in their lower ends. A plurality of relatively narrow endless belts 118 are carried by the rolls already described and pass over the roll 114 of levers 110. These belts may be called the upper belts. Weighted idlers 120 swingable on shaft 90 function to tension the belts 118.

10 Rolls 120 and 122 in the frames 2 and 2' and rolls 124 and 126 on frames 4 and 4' support lower endless belts 118. Tension levers 128 operate on the lower belts.

15 As will be seen in Figs. 1 and 7, the belts are arranged so that their inner adjacent runs carry the lengths of paper so that they are discharged 20 by the rolls 114 and 116 in the lower ends of levers 110.

25 As stated the levers 110 swing back and forth so as to position the rolls 114 and 116 alternately over separate winding mechanisms indicated generally by 130 in Fig. 7 and to be described.

30 The levers 110 are operated by a link 132 connected thereto, as shown, and to a lever 134 on a shaft 136. Cam members 138 on a shaft 140 engage rolls 142 of levers 146 whereby as shaft 35 140 rotates the members 110 are swung back and forth.

35 The winding mechanism will now be described with reference to Figs. 1, 4, 5, 6, 7, 11, 12, 13, 14 and 15. There are two separate complete mechanisms which operate alternately for winding up the lengths of paper. Each winding mechanism consists of two groups of parts. The groups have similar parts and certain parts of one group co-operate with certain corresponding parts of the other group. One complete winding mechanism only will be described.

40 As in Fig. 6, outboard plates 150 are spaced from and secured to frames 4 and 4' by pairs of guide rods 152. A winder head 154 is slideable on each pair of rods 152. Each aligned pair of heads are for one winding mechanism. Upper rods 156 in outer plates 150 extend inwardly therefrom and have fixed to their inner ends spiders 158. These rods reciprocate slightly in plates 150 and may rotate therein.

45 Lower rotatable shafts 160 have keys 162. The heads 154 have sleeves 164 which are provided with slots receiving the keys whereby as the heads reciprocate they move relative to shafts 60 160. Also the heads slide relative to rods 156. Tubes 166 rotate in the upper part of the heads and carry plates 168 on their inner ends. Sleeves 170 in which tubes 166 rotate are fixed in the heads and these have fixed to their inner ends 65 hubs 172. The members 164 are preferably faced with some material such as leather or the like as indicated by 169.

50 Plates 174 are oscillatable on the plates 168 of sleeves 166. A pair of blocks 176 are slideable in the inner faces of plates 168. Hollow winding arbors or tubes 178 extend through the blocks 176 and through eccentrically disposed slots 180 in plate 168. They are threaded on their outer ends and carry nuts 182. The tubes 178 of one 75

head co-operate with those of an opposite head. As the heads reciprocate back and forth the tubes of the heads are carried thereby from a winding position where their inner ends abut to 5 a non-winding position where their ends are widely separated.

In Fig. 6 the heads 154 of the winding mechanism at the front of the machine are in winding position, while the heads 154 of the other winding mechanism are in non-winding position. In 10 the winding position tubes 178 abut, as shown in Fig. 5.

To assure alignment of the tubes in winding engagement, a plug 190 of one tube is received in 15 an opposite tube and the opposite tube carries a plug 192. The tubes 178 also carry perforations 194 in their walls.

As has been explained, the parts 166 are rotatable. They carry the plates 168 and 174 with 20 which tubes 178 are associated so that the tubes are rotated. The length of paper is delivered to a winding mechanism when the tubes thereof are in engagement and in a horizontal plane.

As the plates 174 and 168 are rotated the rods 25 rotate to wind up the paper to form a flat fold. To insure the paper being engaged by the tubes which are hollow the said tubes are connected to a suction means, later to be referred to, and the perforations function to permit the suction to 30 draw the paper against tubes 178. After the length of paper has been wound, the heads are moved outwardly drawing the tubes from within and outwardly at the ends of the wound fold.

In order to vary the center to center distance 35 of the tubes and to thereby vary the width of the fold the nuts 182 may be loosened and plate 174 rotated relative to plate 168. This moves the tubes and blocks 176 in and out.

The blocks 176 have passageways 196 in communication with the hollow tubes 178. The 40 plates 168 have passageways 198 in communication with an annular groove 200 of part 172 and to this passageway there is connected a conduit 202 extending to a suction means.

For rotating the parts for the winding operation there is a sprocket 210 rotatable on a sleeve 212 which is driven from a shaft 214 by a chain 216 engaging a sprocket 218 thereof. A detent 220 in sprocket 210 is pressed outwardly by a 45 spring, as shown.

A driver 221 on a part 224 fixed to part 164 is engaged by a detent 220 so that part 164 is rotated by sprocket 210 when the head is in winding position as shown in Fig. 11. A gear 165 associated with part 164 is in mesh with a gear 167 fixed to part 166 whereby the part 166 is rotated to rotate the tubes.

A female clutch part 226 and sprocket 228 are rotatable on a sleeve 230 of outboard plates 150. 50 These are continuously driven by chains 230' engaging sprockets 232 of shaft 214. When the heads 154 are moved outwardly from winding position towards plates 150 the parts 220 and 221 are disengaged so that the tubes 178 are no longer rotated.

It is desired that when the heads are in their non-winding and arrive at the winding position, the pairs of tubes 178 of each winding mechanism be in a horizontal position and have their 55 axes in the horizontal plane of their axes of rotation. This is accomplished as follows.

A lock 240 is slidable in the head 154, it having a disc part 242. A spring 243 acts on the lock and a rod 244 extending from the lock is arranged to abut a stud 246 when the head is in

its inner or winding position. A notch or slot 248 in part 224 is adapted to receive lock 240. As the head approaches the winding position the rod 244 abuts stud 246 to push the lock 240 inwardly releasing part 224 from the head so it 5 may be rotated.

As the head moves outwardly to non-winding position the lock 240 is urged against part 224. When in full outward non-winding position a male clutch part 169 associated with gear 165 10 enters rotating female clutch 226. Through the clutch parts 164 and 224 are rotated until notch 248 registers with and receives lock 240, whereupon part 224 is locked in certain position holding the upper rotating parts against rotation with the winding tubes in the desired position. The clutch parts are adapted to slip to permit of rotation of part 226 relative to part 165 while the head is in non-winding position a spring 231 15 allowing sufficient movement of the clutch 226 20 to allow of slippage of the said clutch parts.

To jog the paper while it is being wound up the rods 156 are reciprocated slightly to reciprocate members 158 which strikes the edges of the paper on the tubes 178. This is accomplished by 25 a cam 240' on shaft 160 having a projection 242' which engages the lower end of a lever 244'. The lever is pivoted at 246' and its upper end rides in a groove 248 of a collar 250. As lever 244 is 30 swung back and forth by the cam 240, rod 156 35 is reciprocated or vibrated so that member 158 vibrates or jogs the paper.

The heads 154 are reciprocated by levers 266 mounted on pivots 254 for swinging movements and have their upper ends connected by links 256 35 to said heads (see Fig. 4). A central shaft 269 carries arms such as 260 having pins 262 in their outer ends. Connectors 264 have slots at opposite ends, as shown. The slots at inner ends of the connectors receive pins 262 and the slots 40 at their outer ends receive pins 266' of levers 266. There are two shafts, 270 and 272, which are geared together by gears 274. One, such as shaft 270, has an arm 276 carrying a roll 278 which as it rotates clockwise strikes the upper side of a 45 rocker 280 associated with levers 260, to rotate said levers which through connectors actuate levers 266.

Rocker 280 is in winding position in Fig. 4 but is about to be moved to move the heads outwardly to non-winding position. As arm 276 comes to operating position on rocker 280 cam 290 on shaft 272 passes off the right hand end of rocker 280, allowing the rocker to swing counter-clockwise so that levers 260 operate the connectors.

The mechanism just described is for operating the heads of one winding mechanism but there is a duplicate set of parts for operating the heads of the other winding mechanism which 60 are associated with shafts 269, 270 and 272.

One shaft 270 has a bevel gear 292 fixed thereto which is in mesh with a gear 294 on a vertical shaft 296 and said shaft is at its upper end geared by gears 298 and 300 to shaft 140 (see Figs. 6 65 and 7).

As will be observed, the pairs of rods rotate to wind or roll the paper into folds after which by outward movements of the heads the folds are released. They are received on elevators when 70 released and deposited on a conveyor mechanism which moves the folds in the direction of the arrow *a* in Fig. 16. This is accomplished as shown in Fig. 7.

Endless spaced conveyors 310 are supported on 75

carriers 312 of shaft 140, 314', 316, 318 and 320, they carry spaced pushers 311 and travel in the direction of arrow *a*.

Arms 324 and 326 rock on shafts 328 and 330.

- 5 Other arms 332 and 334 rock on shafts 336 and 314. A lever 338 is pivoted to arms 324 and 332 and another lever 340 is pivoted to arms 326 and 334 and fold supports 340 and 342 on levers 338 and 340 are rigid therewith. The arms and levers 10 are so arranged that as they oscillate the supports 340 and 342 move up and down and are maintained in substantially horizontal planes. One support 340 is in upper position for receiving the fold to be released by the winding mechanism 15 at the left after which the arms are operated to lower support 340 so the fold thereon is deposited on the conveyors. Then a support is provided for each winding mechanism and they are alternately operated.
- 20 Cams 350 and 354 on shaft 140 in the rotation of said shaft engage the end of levers 352 and 356. The lever 356 is rigidly associated with arm 324. The arm 352 is connected by link 358 to arm 326. By means of the mechanism described the 25 supports 340 and 342 are operated alternately.

As the folds are deposited on the conveyor or conveyors 310, the upstanding pushers 311 thereof engage the said folds and advance them to the position A in Fig. 7 wherein they pass onto 30 bars 360 carried by a pair of levers 362 and 364. There are preferably two pair of levers for two bars 360. The levers are mounted for rocking movements on shafts 366 and 368. A cam 370 on a rotatable shaft 372 operates on a roll 374 of 35 a lever 376 which is slidable on shaft 372. The said lever 376 is connected to an arm 378 fixed on shaft 368 whereby the cam as it rotates causes the levers 362 and 364 to swing back and forth whereby the bars may receive the folds from 40 conveyor 310 and carry them to the right against upwardly extending stops 380. As the bars 360 move to the right the folds are removed therefrom by the stops so as to drop into a table 382 in which a conveyor in the form of a chain has its 45 upper run traveling in the direction of arrow *b*. This chain carries projections as is usual for engaging the rear ends of the folds.

The table 382 to the right of position A as in Fig. 6 has a narrow portion 386 which is provided with 50 side walls 388. A bracket 390 has rear arm 392 pivoted to brackets 394 and its forward end is forked as at 395 and in this fork a wheel 396 is journaled. As the folds are moved along table 386 they pass under wheel 396 which by movements up and down of bracket 390 bears on the folds. The wheel 396 is rotated, so that it moves the folds, by means of a belt 400 in engagement with a pulley 402 on the shaft of wheel 396 and a pulley 404 driven by belt 406 from shaft 272.

60 The wheel 396 is located at what may be called the buckling position (see Fig. 16) wherein the folds are buckled. This operation is accomplished as follows (see Figs. 6 and 8).

Side plates 410 are pivoted at 412 to table 386 65 to swing between horizontal and elevated positions. As folds are conveyed to the buckling position the plates are moved to elevated position the wheel 396 being on the folds. As side plates 410 are elevated they move the longitudinal sides of 70 the folds upwardly forming more or less of a U as shown in dotted lines in Fig. 8. An arm 414 pivoted for rocking movements carries a stud 416 in its outer end and connectors 418 pivotally connected at their upper ends to the plates 75 410 have lower slotted ends receiving stud 416.

A cam 420 on shaft 372 acts on a roll 415 of lever 414 whereby the connectors are operated to actuate the plates.

After the folds are buckled they are fed forwardly and inserted in a wrapper of tubular form. The tubes are in flat form in a stack and are fed successively to fold receiving position wherein they are opened up. After a fold is inserted in a tube the completed package is moved to a stack thereof. It will be understood that as a fold is fed onto the buckling mechanism it moves a previously buckled fold along.

At the right hand end of the machine, as shown in Fig. 6, there is a tube magazine formed by vertical side walls 420'. This magazine is for a 15 stack of wrappers or tubes *T* in flat condition such as shown in Fig. 16. A table or slide 422 is reciprocable in guides such as 423 in frames 3 and 3' and transversely of the direction of travel of the folds. The stack of superposed tubes in 20 the magazine rests on the table 422. Suction openings 424 are provided in the table 422 which when it is in its rear position underlie the stack of flat tubes. As the slide 422 moves forwardly or to the right, the suction action causes the lowermost tube to be carried by the slides from beneath the stack to fold receiving position at the right of a plurality of trips 425. As the slide 422 moves to the left the edge of the fold brings up against the trips. As the slide reaches its leftmost position the fold is dropped onto the low part of the slide and the higher part of the slide is in position to take on another fold. When a fold is on the lower part of the slide it is in receiving position and is opened up and held in open relation 25 while a buckled fold is inserted therein. The plates 410 which buckle the folds are held in buckling relation while the folds are advanced 30 therefrom into the opened up tubes.

A carriage 430 is slideable up and down in 40 brackets such as 434. The carriage is of some length to overlie the tubes on the slide in receiving position. The slide carries a series of spaced suction nozzles 436. The slide 422 has a plurality of suction openings 421 which underlie the fold 45 thereon. With a tube in flat condition on table 422 and with the nozzles and openings connected to suction means the member 430 descends so the nozzles bear on the tube and then as it elevates the flat carton is acted upon by suction so that 50 it is opened up as at C in Fig. 16. The fold is then fed forwardly into the tube and the suction means releases the tube so it assumes a flat condition on the flat fold.

A lever 440 fixed to a shaft 440 journaled in a 55 bracket 442 has its forward end connected to member 430. As the lever swings the member 430 and nozzles are moved up and down. A link 444 connected to lever 440 is connected to a lower swinging lever 446 which is actuated by a cam 448 operating on a roll 448 thereof, the cam 448 being fixed to shaft 372.

After a fold is inserted in a tube to complete the package, the package is moved to the right (see Fig. 9) to the bottom of a stack of finished 65 packages and in the direction of arrow *y* shown in Fig. 16.

This is accomplished by transporters such as 450 on the upper ends of bars 452. Arms 454 rocking on shafts 456 and 458 have their outer 70 ends connected to bar 452. A lever 460 swinging on shaft 458 has a roll in contact with a cam 462 on shaft 372 and its upper end is connected by link 464 to a lever 466 rigid with upper lever 454. As lever 460 is swung back and forth by its 75

cam the levers 454 swing up and down so the transporters pass through a more or less elliptical path underneath the package on slide 442 and elevating it. The slide 422 as it reaches the 5 position at the extreme right moves the package over transporter 450.

A lever 470 swingable on pivot 472 carries a bar 474 on its upper end and from this there extend a plurality of supporting rods 476. This 10 lever swings back and forth from the position shown in Fig. 10 to a position at the right thereof to carry the rods beneath a table 476.

The stack is supported by the rods 476 and by the transporters. That is, as the transporters 15 elevate a package the rods 476 move to the right from beneath the stack so the package on the transporters support the stack. Then the rods move to the left beneath the package on the transporters and support the stack until it is 20 again supported by the transporters. Thus the slide moves a completed package to the right and over the transporters which elevate the package so it becomes the bottom one of a stack.

A cam 478 on shaft 372 engages a roll of a 25 lever 480 rocking on shaft 458 and this is connected by a link 482 to lever 470. A link 484 is connected to slide 422 and a lever 486 while a link 488 connects lever 486 to a lever 490 rocking on shaft 458'. This latter lever is operated by 30 a cam 492 on shaft 372.

The nozzles 436 are connected by conduits 437 to a header 439 and said header is connected to a pipe 441. A conduit 443 connects opening 424 to pipe 441 while a header 443' is connected by 35 several conduits 445 to the several openings 421 in the slide while a conduit extends from header 443' to pipe 441.

The pipe 441 is connected to a suction device such as 500 at the rear end of the machine. This 40 is driven from the motor 26 by means of the belt and pulley drive consisting of pulleys 502, 504, and belt 506. A valve mechanism V in pipe 441 has a part operable by shaft 372 whereby the different units are in timed relation connected 45 to the course of suction. Thus the openings are under the influence of suction for the various operations.

A pulley 510 of shaft 28 carries a belt 512 which engages a pulley 514. A gear 516 associated with 50 pulley 514 meshes with a gear 518 which rotates with another gear 520. The latter gear 520 meshes with a gear 522 and this rotates with a gear 524 in mesh with a gear 526 on shaft 140 whereby said shaft is driven (see Fig. 1).

55 A pulley 528 associated with gears 522 and 524 carries a belt 530 which engages a pulley 532. A pulley 536 has a belt 534 therearound engaging a pulley 538 of shaft 372 whereby this shaft is driven for operating the buckling and feeding 60 mechanism last described.

A frame against which the completed folds may rest is shown in Fig. 10. It consists of a bar 540 extending between brackets 434, links 542 pivoted at opposite ends to said bar and to vertical 65 members 544, a link 546 pivoted at opposite ends to members. The pivots are arranged so that the members may be moved from the full line position and the position shown in dotted lines and positions therebetween and will hold the members 70 in said positions.

While I have described the invention in great detail and with respect to a preferred form thereof, it is not desired to be limited thereto since many changes and modifications may be made 75 therein without departing from the spirit and

scope of the invention. What it is desired to claim and secure by Letters Patent of the United States is:

1. In a machine of the class described comprising in combination, means for winding lengths of material in folds, means for feeding successive lengths of material to the winding means, the said winding means including rotatable members reciprocable between winding and non-winding positions, pairs of winding members carried by said members adapted to have their inner ends in abutment when in winding relation and in separated relation when in non-winding relation, and jogging members associated with the winding members and reciprocable relative thereto for 10 engaging and jogging material as it is wound on said tubes. 15

2. In a machine of the class described comprising in combination, means for winding lengths of material in folds, means for feeding successive 20 lengths of material to the winding means, the said winding means including rotatable members reciprocable between winding and non-winding positions, pairs of winding tubes carried by said members adapted to have their inner ends in 25 abutment when in winding relation and in separated relation when in non-winding relation, jogging members associated with said tubes and reciprocable relative thereto for engaging and jogging material as it is wound on said tubes, 30 means for rotating and reciprocating said tubes and means for reciprocating said jogging members.

3. In a machine of the class described comprising in combination, means for winding 35 lengths of material into folds, means for feeding successive lengths of material to the winding means, the said winding means including rotatable members reciprocable between winding and non-winding positions, pairs of winding members carried by said members adapted to have their inner ends in abutment when in winding relation and in separated relation when in non-winding relation, engageable means associated with the inner ends of the winding members to hold the said members in alignment when in winding relation, and jogging members associated with the winding members and reciprocable relative thereto for engaging and jogging material as it is wound on said tubes. 40 45

4. In a machine of the class described comprising in combination, means for winding lengths of material into folds, means for feeding successive lengths of material to the winding means, the said winding means including rotatable members reciprocable between winding and non-winding positions, pairs of winding members carried by said members adapted to have their inner ends in close adjacency when in winding relation and in separated relation when in non-winding relation, and jogging members associated with the winding members and reciprocable relative thereto for engaging and jogging material as it is wound on said tubes. 50 55 60

5. In a machine of the class described comprising in combination, a support, a rotatable member, winding members extending axially therefrom for winding a web of material into a fold, a jogger reciprocable relative to said winding members for engaging an edge of a fold, a 70 drive shaft, engageable connections between said shaft and rotatable member, and engageable means between said jogger and drive shaft whereby the latter operates the former.

LEONARD HOPKINS. 75
